UNITED STATES PATENT OFFICE.

GEORGE W. YUNG, OF DUNKIRK, NEW YORK.

INSTRUMENT FOR LAYING OUT THE EDGES OF CUTTER-HEAD KNIVES.

1,090,006.

Specification of Letters Patent. Patented Mar. 10, 1914.

Application filed March 26, 1913. Serial No. 757,001.

To all whom it may concern:

Be it known that I, GEORGE W. YUNG, a citizen of the United States, residing at Dunkirk, in the county of Chautauqua and 5 State of New York, have invented certain new and useful Improvements in Instruments for Laying Out the Edges of Cutter-Head Knives, of which the following is a specification.

10 The object of this invention is to provide simple and reliable means for laying out the cutting edges of the knives used on rotary cutter-heads to produce moldings of different patterns.

15 My invention is particularly intended for use in the formation of the knives of rotary cutters having what are known as square or polygonal heads on which the knives are arranged tangentially relatively to the axis 20 of rotation. In such cutters when used to produce moldings the knives being arranged tangentially on the head act on the stock at an angle and hence the different parts of the irregular cutting edge are disposed in dif-

25 ferent vertical planes when the knife enters the stock. Consequently the recesses in the cutting edge must be deeper than the height of the corresponding raised parts of the moldings and the depths of these recesses 30 must increase proportionately. This is well understood by those skilled in the art and great difficulty is usually experienced in laying out the edges of knives of this class in order to adapt them to produce moldings 35 of the desired patterns. It is most commonly done at present by successive trials and grindings until the required edge is produced, although instruments have heretofore been suggested for facilitating to

40 some extent the operation. I have produced an instrument of very simple construction which enables me to determine without the use of scales or similar measuring means and with absolute accuracy the 45 required dimensions for the pattern of a knife to produce any kind of molding by means of a rotary cutter-head of the type before mentioned.

45 The manner in which the instrument is 50 preferably constructed and operated is hereinafter explained, but many of the details of construction may be changed or varied without departing from the broad features of the improvement which are pointed out 55 in the claims.

In the accompanying drawings:—Figure

1 is a perspective view of the preferred form of my instrument. Fig. 2 is a plan view of the base-plate with the measuring rod shown by dotted lines, and partly broken 60 away. Fig. 3 is a plan view of the measuring rod. Fig. 4 is a view partly in side elevation, partly in longitudinal section, and with parts broken away, of the measuring rod as preferably constructed. Fig. 5 is a 65 diagram illustrating a piece of molding in vertical section, and a knife of a square cutter-head having its edge properly formed to produce the molding. Fig. 6 is a plan view of the measuring rod on an enlarged 70 scale, showing more fully the devices for varying its length. Fig. 7 shows a section on the line 7—7 of Fig. 6.

The instrument comprises a base-plate A, and a measuring rod B which is pivotally 75 connected with the base-plate at a point *a* (Fig. 2) representing the center of rotation of the cutter-head to which the knife is applied. On the base-plate is marked a line *z* which would, if produced, pass through 80 said point *a*. The base-plate is also marked at *y* to represent a line registering with the plane of the inner face of the knife and also passing through the adjacent corner of the cutter-head. The line *y* is technically 85 called the knife line and the lines *z* and *y* meet at a point corresponding with the corner of the cutter-head at an angle of 45°. At *w* means is provided, such as a dot, to indicate or represent the edge of the knife 90 or a point on the knife line *y* intersected by a clearance line *z'*.

The measuring rod B may be provided with a knob *b* to serve as a handle and said rod is provided with means such as a shoulder *b'* to assist in the measuring operation as will be hereinafter described. Said rod is also provided with means such as a straight edge *c* for indicating a straight line radial to the center of rotation and which 100 may be made to register with the radial line *z*, in the manner shown in Figs. 1 and 2.

Figs. 1 and 2 indicate how the instrument may be adapted for use in laying out the knives for cutter-heads of different sizes. 105 The lines *l*, *m*, *n*, *o*, *p*, *q*, *r*, *s*, *t*, *u* indicate cutter-heads of different sizes. Thus the square within the lines *l*, *r*, *u*, *o* may indicate a 3 $\frac{1}{2}$ " head. The next square may indicate a 3 $\frac{3}{4}$ " head, and so forth. Any sizes of 110 heads may be indicated in this way and the instrument is adapted for use in connection

with heads of all sizes. When thus used the base-plate is provided with additional pivot holes a' , a^2 , a^3 corresponding in position to the centers of rotation of the different heads, and the measuring rod is provided with corresponding additional holes d' , d^2 , d^3 . The pivotal connection between the measuring rod and the base-plate may be made in any suitable way, as by a screw E.

- 10 It is sometimes desirable to lengthen and shorten the rod for the purpose of adapting the measurements to different amounts of clearance given to the knives. This may be done in various ways, but preferably for 75 this purpose I form the rod in two parts, b^2 , b^3 which are telescopically connected with each other in the manner shown; that is to say, the part b^3 is formed with a tongue b^4 which enters a groove b^6 in the part b^2 .
 15 20 The part b^4 is formed with a slot b^5 and through this slot extends a screw B^2 which receives a clamp nut B' . By these devices the measuring rod may be lengthened or shortened and firmly connected. If desired 80 a scale B^3 may be employed.

In Fig. 5 I have shown a well known form of molding M. In order to lay out the pattern for the cutting edge of the knife K for producing this molding by the use of my 85 instrument, I proceed as follows: Measurements are taken on the lines 1—2, 3—4, 5—6, 7—8, 9—10 in the manner indicated. For taking the measurement 9—10 for example, I proceed as follows: I measure from 90 the base line of the molding along the line 9—10 by means of dividers, calipers or other suitable instruments, indicated at D in Fig. 1, and then bring the edge c of the measuring rod into register with the line z, place 95 one point of the dividers against the shoulder b' and the other point against the straight edge c (Fig. 1). I then turn the rod to the right until the outer point of the dividers reaches the line y. This point is 100 indicated at e^2 in Fig. 2. I then turn the measuring rod out of the way, retain the outer point of the dividers on the knife line y at e^2 and move the other point until it registers with the point α on the base-plate, 105 which point corresponds with the edge of the knife and is also located on the clearance line z' which may also be indicated on the base-plate. This extension of the dividers is just sufficient to indicate the increase in 110 the depth of the recess to be made in the knife. This measurement is then indicated 115 on the pattern or diagram, and inasmuch as it is assumed that the other measurements at 1—2, 3—4, etc., have been made and adjusted, the result will be that when the 120 measurements are recorded the knife pattern indicated in Fig. 5 will be produced, which is of the exact shape required to produce the molding M shown in the same figure. I 125 have indicated on the drawings in Fig. 2 a

point marked y' . The distance between the point e^2 and y' is equal to the distance from b' to the point c' , which is the same as the distance 9—10 in Fig. 5. The distance between y' and α indicates the increase in the 70 dimensions and this distance or increase corresponds precisely with the distance between the point 10 in Fig. 5 and the adjacent edge of the knife.

No scales or similar devices are used 75 which would confine the measurements to definite limits and the instrument is of the simplest character, being adapted for use in connection with cutter-heads of all sizes.

It will be understood that it is not necessary to place all the marks and lines on the base-plate that I have shown in the drawings. Some of these can obviously be omitted and the measuring rod may be differently constructed. 80

I claim as my invention:

1. An instrument for laying out the edges of cutter-heads, comprising a base plate provided with means for indicating the center of rotation of a cutter-head, means for indicating a radial line extending from said center of rotation through a corner of the cutter-head, means for indicating a knife line extending at an angle of 45° at the corner of the cutter-head to said radial line, and means for indicating on said knife line the line of clearance of the cutter, in combination with a measuring rod pivotally connected with the base plate at the point indicating the center of rotation of the cutter-head and which is provided with means for indicating a line adapted to register with said radial line and also with means for indicating a point which is adapted to register with the point on said knife line intersected by said clearance line. 100

2. An instrument for laying out the edges of cutter-heads, comprising a base plate provided with means for indicating the center of rotation of a cutter-head, means for indicating a radial line extending from said center of rotation through a corner of the cutter-head, means for indicating a knife line arranged at an angle at the corner of the cutter-head to said radial line, and means for indicating on said knife line the line of clearance of the cutter, in combination with a measuring rod pivotally connected with the base plate at the point representing the center of rotation of the cutter-head and which rod is provided with a straight edge adapted to register with said radial line and also with a shoulder which is adapted to register with said point on the knife line intersected by the clearance line. 110

3. An instrument for laying out the edges of cutter-heads, comprising a base plate provided with means for indicating a knife line, means for indicating a radial line extending from a point representing the cen- 115

- ter of rotation of the cutter-head through a corner thereof, means for indicating the clearance line of the cutter, and a measuring rod provided with means for pivoting it to the base plate at different points representing different centers of rotation of cutter-heads of different sizes and which rod is provided with means for indicating a line adapted to register with said radial line and also with means for indicating a point which traverses the clearance line of the cutter.
4. An instrument for laying out the edges of cutter-head knives, comprising a base plate provided with means for indicating the center of rotation of a cutter-head, means for indicating a radial line extending from said center of rotation through a corner of the cutter-head, means for indicating a knife line, and means for indicating on said knife line the line of clearance of the cutter, and a measuring rod pivotally connected with the base plate at the point representing the center of rotation of the cutter-head and which is provided with means for indicating a line adapted to register with said radial line and with means for indicating a point of measurement, and devices for adjusting the length of said rod.
- In testimony whereof, I have hereunto subscribed my name.
- GEORGE W. YUNG.
